UNITED STATES PATENT OFFICE.

JACOB MILTON WOODLING, OF MORGANTON, NORTH CAROLINA.

BOILER-FURNACE.

Specification of Letters Patent. Patented Mar. 31, 1914.

1,091,996.

Application filed May 4, 1912. Serial No. 695,087.

To all whom it may concern:

Be it known that I, JACOB M. WOODLING, a citizen of the United States, and a resident of Morganton, county of Burke, State of North Carolina, have invented certain new and useful Improvements in Boiler-Furnaces, of which the following is a full and clear specification, reference being had to the accompanying drawings, in which—

10 Figure 1 is a view partly in plan and partly in horizontal section showing my invention applied to a twin boiler furnace; Fig. 2 is a vertical longitudinal sectional view of the same; Fig. 3 a vertical sectional view through the bridge wall; Fig. 4 a detail perspective view of a form of grate which I prefer using with my furnace.

15 The object of this invention is to so construct the apparatus that the maximum steaming capacity shall be obtained from the fuel, and a further object is to adapt the furnace for using a combination fuel consisting of coal and certain waste fibrous products such as saw dust, tan-bark, etc., 20 as more fully hereinafter set forth.

25 In the drawings, *a* designates the ash pit having front openings *b* for the removal of the ashes and the supply of air to the furnace grate *c*, these openings *b* being unprovided with doors so that the air supply shall be unrestricted at all times. The grate *c* 30 may be of any suitable construction but I prefer using railway rails *d* as transverse supporting bars, upon which are mounted a series of grate bars *e* which taper in cross section downwardly to prevent buckling, these bars being spaced properly by suitable lugs formed on the side faces thereof.

35 Coal fuel is introduced through the charging openings *f* which are covered by the usual doors *g*. The waste-products fuel (such as saw dust, etc.,) is introduced into the fire box through a series of charging tubes or holes *h* formed in the roof *i* of the fire box, each of these charging holes being 40 provided with a removable cover *j*. Any number of these charging holes may be employed and they may be arranged in any suitable manner to the end that the fibrous or vegetable fuel may be distributed 45 properly on the grate surface. It will be observed however that these charging holes are spaced a considerable distance away from the front of the furnace, so that coal fuel 50 alone can be spaced upon the front part of the grate surface, whereby a hot coal fire

may at all times be maintained and thus promote and insure the complete combustion of the waste-products fuel.

55 It will be observed that the roof *i* of the fire box inclines upwardly and backwardly on its inner face, thereby enlarging the rear opening of the fire box and thus preventing puffing and choking of the furnace by insuring a free and adequate outlet for the products of combustion during the times when a very hot fire is maintained. It will be observed that to assist this free discharge of the products of combustion during very hot fires, the top of the back wall is approximately level with the grate and also that the distance between the roof and the grate at the front end of the fire box is less than the distance between the roof and the top surface of said back wall, so that when fuel is piled upon the grate surface the space above the fuel will widen or enlarge backwardly. From the back wall *k* of the fire box, the bottom *l* of the combustion chamber inclines sharply upwardly to a suitable point beyond 60 the front end of the boiler *m*, at which point it joins a bridge wall *n* which is curved on its upper surface to conform somewhat to the convex curvature of the boiler. With this upward slope *l* and the curved bridge wall, 65 it will be observed that the hot products of combustion are caused to be thrown up and around the boiler and thus obtain from the products a maximum of heating effect. From the bridge wall, the bottom *o* of the 70 combustion chamber slopes downwardly to the rear end of the furnace to the end that the products of combustion shall have a free outlet back of the bridge wall and shall be caused to spread before they pass up into the 75 space *p* at the back of the furnace, whence they enter the flues of the boiler. At the front of each boiler is a smoke box *q*, and these two smoke boxes are connected at one side to a central horizontal flue *r* which leads 80 backwardly to the stack *s*. At the juncture of each smoke box with the flue *r* is a damper *t* for controlling the draft. By means of these dampers the draft is controlled entirely, there being no draft doors or dampers 85 at the openings *b* of the ash pit. This construction enables the furnaces to be perfectly controlled without the introduction of cold air into the fire boxes or under the boilers, whereby the operations of the furnaces may 90 be controlled and the heat retained in the combustion chamber and the boiler flues.

It will be understood that my invention is applicable to single boiler furnaces as well as to the double boiler furnaces illustrated. Where the double or twin boilers are used, I place at the juncture between the two smoke boxes *q* a vertical deflector *u* which is approximately V-shaped in cross section and has its apex extended into the forward or mouth end of the flue *r*. This deflector forms two throat-like passages *v* through which the products of combustion pass upon entering the stack flue *r*. In these throats or passages are located the dampers. The object of this deflector is to prevent one fire 10 when that fire is much stronger than the other from choking or retarding the fire in the opposite furnace, this being done by directing the products of combustion, from each smoke box in a line directly backward 15 in the stack flue so that should one fire be stronger than the other it will exert a sort of suction or forced draft action upon the slower fire, thereby making each furnace 20 complementary to the other.

It will be understood that some of the fea- 25

tures of my invention are applicable not only to single boiler furnaces but also to furnaces adapted for burning coal alone.

Having thus described my invention, what I claim as new and desire to secure by Let- 30

ters Patent, is—
A twin boiler furnace embodying a smoke box at the forward end of each boiler, a stack flue connected to said smoke boxes and extending rearwardly between the boilers, a 35 stack connected to the rear end of said flue, a deflector at the juncture of the smoke boxes and the flue, said deflector being approximately V-shaped in horizontal section and having its forward edge extending toward 40 the center of the front end of the flue, and a damper in each of the throats or passages formed by said deflector.

In testimony whereof I hereunto affix my signature in the presence of two witnesses. 45

JACOB MILTEN WOODLING.
